UNITED STATES PATENT OFFICE.

JOEL C. WELLS, OF SOUTHBRIIDGE, MASSACHUSETTS.

DESIGN FOR A LENS-CLIP.

51,911.

Specification for Design.

Patented Mar. 26, 1918.

Application filed October 26, 1917. Serial No. 198,736. Term of patent 14 years.

To all whom it may concern:

Be it known that I, JOEL C. WELLS, a citizen of the United States, residing at Southbridge, in the county of Worcester and State of Massachusetts, have invented a new and original ornamental Design for a Lens-Clip, of which the following is a specification, reference being made to the accompanying drawings, forming a part thereof.

Figure I represents a view of one side of a lens clip or fitting embodying my novel design.

Fig. II represents a plan view thereof.

Particular attention is invited to the dome shaped enlargement at the ends of the clip

ears in combination with the gradually tapering sides having the beveled or inclined faces with the central meeting edge or dividing point which terminates adjacent the edge of the protuberance.

I claim:

The ornamental design for a lens clip substantially as illustrated and described.

In testimony whereof, I affix my signature in the presence of two witnesses.

JOEL C. WELLS.

Witnesses:

E. M. HALVORSEN,
H. E. COLEMAN.
